(57) **CLAIM**

The ornamental design for a shoe, as shown and described.

DESCRIPTION

FIG. 1 is a front perspective view of a shoe showing my new design;

FIG. 2 is a left side view of the shoe shown in FIG. 1;

FIG. 3 is a right side view of the shoe shown in FIG. 1;

FIG. 4 is a front view of the shoe shown in FIG. 1; and,

FIG. 5 is a top view of the shoe shown in FIG. 1.

The broken line showing of the heel, sole, portion of the upper, and portion of the front is for illustrative purposes only and forms no part of the claimed design.

1 Claim, 5 Drawing Sheets
